(57) **CLAIM**

The ornamental design for a dental scanner, as shown and described.

DESCRIPTION

The patent or application file contains at least one drawing executed in color. Copies of this patent or patent application publication with color drawing(s) will be provided by the Office upon request and payment of the necessary fee.

1. Dental scanner

1.1 : Perspective

1.2 : Front

1.3 : Back

1.4 : Left

1.5 : Right

1.6 : Top

1.7 : Bottom

The portion of the design shown in the color blue is for the purpose of illustrating portions of the dental scanner that form no part of the claimed design.
